UNITED STATES PATENT OFFICE.

HIRAM W. HAYDEN, OF WATERBURY, CONNECTICUT, ASSIGNOR TO THE
ROGERS & HAMILTON COMPANY, OF SAME PLACE.

DESIGN FOR A SPOON OR FORK HANDLE.

SPECIFICATION forming part of Design No. 17,241, dated April 5, 1887.

Application filed February 17, 1887. Serial No. 228,006. Term of patent 7 years.

To all whom it may concern:

Be it known that I, HIRAM W. HAYDEN, a citizen of the United States, residing at Waterbury, in the county of New Haven and State of Connecticut, have invented and produced a new and original Design for Spoon and Fork Handles, of which the following is a specification, reference being had to the accompanying drawing, which forms a part thereof.

10 In the drawing is shown a spoon whose handle is ornamented in accordance with my design.

The leading feature of my design is the row or series of raised oval bead-shaped figures, lettered A, which appear upon and extend along the spoon-shank from the juncture of the latter with the bowl to the point where the shank commences to widen into the handle. The beads which make up the pattern are as

long as the spoon-shank is wide on the top, and, 20 collectively, the pattern occupies the entire top surface of the spoon-shank, as is shown in the drawing.

I claim—

A design for spoon-handles and the like, the 25 same consisting of the beaded figure, as described, covering the entire top surface of the spoon-shank and extending from the juncture of the shank and bowl to the point where the handle develops out of the shank, substantially 30 as illustrated and described.

In testimony whereof I affix my signature in presence of two witnesses.

HIRAM W. HAYDEN.
